UNITED STATES PATENT OFFICE.

HENDRICKS DRAKE, OF CAMPTON, KENTUCKY, ASSIGNOR OF ONE-HALF TO NEWTON ALEXANDER, OF CAMPTON, KENTUCKY.

ENGINE.

No. 906,119.

Specification of Letters Patent.

Patented Dec. 8, 1908.

Application filed October 11, 1906. Serial No. 338,517.

To all whom it may concern:

Be it known that I, HENDRICKS DRAKE, a citizen of the United States, residing at Camp-
ton, in the county of Wolfe and State of Ken-
tucky, have invented a new and useful En-
gine, of which the following is a specifica-
tion.

This invention relates to steam engines, and has for its principal object to provide
10 improved means for controlling the operation
of the engine.

A further object of the invention is to pro-
vide an improved valve operating mechanism, in which eccentrics, cranks and other
15 devices receiving motion from the main shaft are dispensed with, the piston serving at or
near the completion of each stroke to shift
the position of the valve.

A still further object of the invention is to
20 provide an improved means for automatically
reversing the engine in case of sudden
increase in the load beyond the capacity of
the engine.

A still further object of the invention is to
25 provide a reversing or controlling mechanism
which receives motion from the connecting
rod where the engine is driven back by
sudden excess in the load.

With these and other objects in view, as
30 will more fully hereinafter appear, the invention
consists in certain novel features of con-
struction and arrangement of parts, here-
inafter fully described, illustrated in the
35 accompanying drawings, and particularly
pointed out in the appended claims, it being
understood that various changes in the form,
proportions, size and minor details of the
structure may be made without departing
40 from the spirit or sacrificing any of the ad-
vantages of the invention.

In the accompanying drawings:—Figure 1
is a sectional elevation of a steam engine con-
structed in accordance with the invention.
Fig. 2 is a detail perspective view of one of
45 the tappet arms.

Similar numerals of reference are em-
ployed to indicate corresponding parts
throughout the several figures of the draw-
ings.

50 The engine is provided with a suitable base
or sole plate 10, carrying a cylinder 11, and
cross head guides 12.

In the cylinder is a piston 15 connected by
a rod 16 to a cross head 17; and the latter is

connected by a rod 18 to the main crank 55
shaft.

In the steam chest is arranged an ordinary
D-valve 20 controlling the flow of steam
through cylinder ports 21—22, and the ex-
haust port 23. This valve is carried by or 60
connected to a rod 24 that extends out
through both ends of the steam chest, and at
the crank shaft end is connected to a lever
26, the lower end of which carries a pin 27
extending through the cylinder head and ar- 65
ranged in the path of movement of the piston
15. The opposite end of the valve rod is
connected to a lever 28, the lower end of
which carries a tappet pin 29 extending
through the rear cylinder head and disposed 70
in the path of movement of the piston.
During the operation of this portion of the
mechanism, the piston is operated under full
steam pressure for nearly the whole of the
stroke, and just before reaching the end of 75
the stroke engages with one or other of the
tappet rods 27—29, and shifts the position of
the valve.

At one side of the cross head guides, adja-
cent to the crank shaft end of the cylinder, 80
is a pivot pin 30, on which is mounted a two-
armed lever 31. This lever is connected to a
pair of arms 32—33 that extend along paral-
lel with the cross head in the direction of the
crank shaft, and are provided with inwardly 85
extending arms which carry tappets 34 and
35—respectively. These tappets are held in
vertical position by small springs 36 and are
arranged to yield outwardly or in the direc-
tion of the crank shaft, but are held from in- 90
ward yielding movement. On the connect-
ing rod 18 is a double tappet or block 38 that
is arranged to engage with the tappets 34
and 35. During the out stroke of the piston,
while the connecting rod is moving in the 95

direction indicated by the arrow, the tappet
34 will be engaged by the block 38, and will
yield to permit the passage of the block, and
during movement of the crank shaft in the
reverse direction, the block will engage the 100
tappet 35. If, however, the work which the
engine is called upon to perform is in excess
of its capacity, the connecting rod will be
driven back and the block 38 will engage
either the tappet 34 or 35, depending on the 105
direction of rotation of the crank shaft, and
will positively move one or other of the rods
32—33.

At a point near the end of the frame is pivoted a lever 40, the upper end of which is connected by a link 41 to the valve rod. The valve rod is provided with a pin 42 and 5 the adjacent end of the link has an elongated slot 43 which will permit free movement of the valve rod as it shifts from one position to the other during the ordinary operation of the engine, without bringing the pin into engagement with the end walls of the slot 43.

The lever 40 has a suitable handle, so that the lever may be manually manipulated for the purpose of reversing the engine. The lower end of this lever is connected to the lever 31 by a rod 43', the connection being such that when the valve is adjusted for movement of the engine in the direction indicated by the arrow, the tappet 34 will be advanced in the direction of the crank shaft, and the tappet 35 will be moved away from the crank shaft. In this position the tappet 34 will be directly in the path of movement of the block 38, and will be engaged by the latter each time the crank shaft rotates. 25 The tappet 35, however, will be out of the path of movement of the block 38, and will not be engaged by said block.

If the engine is driven back by excess load while the connecting rod is moving in the direction indicated by the arrow, the block 38 will come into contact with the forward face of the tappet 34 and the latter being held rigid, movement will be transmitted to the rod 32, thereby rocking the lever 31, and 30 this movement is transmitted through the rod 43 to the reversing lever 40, thus shifting the position of the valve 28 and reversing the engine. If on the other hand the rod is moving in the direction contrary to that indicated at the arrow, the tappet 35 will be engaged, and the reversing lever will be moved in the other direction to effect reversal of the direction of rotation of the crank shaft.

45 When the parts are in the position shown in Fig. 1, the valve 20 has moved to such position as to open the port 21, so that steam is flowing into the left hand end of the cylinder, while steam is exhausting from the right hand end of the cylinder, and is passing through the cavity of the valve into the exhaust port 23. The connecting rod 18 is moved in the direction indicated by the arrow and the piston is at half stroke.

55 If the engine continues its ordinary operation, the piston 15 will engage the rod 27 as it nears the completion of its stroke, and the position of the valve will be shifted, so as to open the port 21 to the exhaust and establish communication between the steam chest and the right hand end of the cylinder, in order to reverse the direction of movement of the piston.

It frequently happens in rolling mill operations that when the ingot is being attacked

by the rolls, too much draft is given the latter. The result of this is a jamming of the ingot in the rolls and it is driven back to a certain extent with the engine driving said rolls. It then becomes necessary to reverse 70 the engine by hand so that the ingot may be drawn out from between the rolls. To obviate this manual reversion of the engine when the work which it is called upon to perform is in excess of the capacity of the engine, and if persisted in would result in breakage of the engine or some of its connections, the piston rod instead of completing its stroke, will be forced backward and the block 38 will engage the tappet 34 and will shift the rod 32 endwise in the direction of the cylinder. This movement will be transmitted through the lever 31 to the connecting rod 43, moving the latter in the direction of the cross head and transmitting movement 85 to the lever 40 which, in turn, will shift the valve rod 24 and valve 20 from the left, it being remembered that at this time the valve 20 is in such position that steam is entering from the chest through the port 21. 90 When the valve 20 is shifted, however, the port 21 is placed in communication with the exhaust and communication is established between the steam chest and the port 22, so that steam is admitted to the right hand end 95 of the cylinder before the piston completes the stroke which it has started, and before the crank pin moves across the center and in this way the direction of rotation of the engine will be reversed.

When the engine is operated in the direction indicated at the arrow, the upper tappet 34 is arranged in such position as to be engaged by the block 38 at each revolution, while the block 35 is drawn rearward in the 105 direction of the cylinder and is out of the path of the connecting rod and the lower block 38 as the piston moves backward, it being observed that the lever 31 is centrally pivoted, and when one of the blocks is advanced, the other block is drawn rearward out of operative position.

An engine constructed in accordance with this invention may be operated with economy owing to the reduction in the number 115 of parts in frictional contact and the automatic safety device will prevent strain or break down of the engine when the work which the engine is called upon to perform is in excess of its capacity.

I claim:

1. The combination in a steam engine, of the cylinder, a piston therein, a cross head connected to the piston, a connecting rod, a crank shaft, a block carried by the connecting rod, a reversing lever, and means arranged in the path of movement of the block and connected to the reversing lever to effect reversal of the engine in case of excess load.

2. The combination in a steam engine, of

a cylinder, a piston therein, a cross head connected to the piston, a connecting rod, a crank shaft, a block on said connecting rod, a pair of rods adjacent to the cross head, tappet arms carried by the rods and yieldable in one direction, a lever to which the rods are connected, and an engine reversing member connected to said lever and serving to adjust one or other of said rods to opera-

tive position with relation to the connecting rod block.

In testimony that I claim the foregoing as my own, I have hereto affixed my signature in the presence of two witnesses.

HENDRICKS DRAKE.
